UNITED STATES PATENT OFFICE.

MARTIN MERKLEN, OF NEW YORK, N. Y.

CHAIR SEAT AND BACK.

SPECIFICATION forming part of Letters Patent No. 228,662, dated June 8, 1880.

Application filed February 19, 1880.

To all whom it may concern:

Be it known that I, MARTIN MERKLEN, of the city, county, and State of New York, have invented certain new and useful Improvements 5 in Chair Seats and Backs, of which the following is a specification.

In the accompanying drawings, Figure 1 represents a perspective view of a chair with my improved chair seat and back, and Fig. 2 is a 10 detail horizontal section of the seat.

Similar letters of reference indicate corresponding parts.

This invention relates to an improved chair seat and back of a light yet strong and durable character, which is adapted for parlor and other chairs; and it consists of a chair seat and back constructed of a series of plain rounds 15 passing through holes of transverse rounds, having enlarged portions at the points of intersection.

Referring to the drawings, A represents the outer frame of a chair seat or back; B, a series of plain round pieces or strips, and C a series of transverse pieces or strips, which are 20 provided with spherical or other enlargements or knobs, *a*, at the points of intersection, said enlargements or knobs being perforated to admit the passage of the rounds B.

The series of plain rounds, as well as the 25 cross-rounds, are let into mortises of the seat

or back frame, and form therewith a stiff yet light and airy seat and back.

Both the plain and the perforated cross-rounds are turned off on the lathe, and readily connected with each other by passing the 35 plain rounds through the enlarged perforated portions of the cross-rounds. A peculiar style of the chair seat and back is thereby obtained, which, when properly finished off in black and gold, is adapted for parlor-chairs, and for rustic 40 chairs and sofas when made in light plain wood.

Having thus described my invention, I claim as new and desire to secure by Letters Patent—

In chair seats and backs, the combination 45 of an outer supporting-frame with rounds having enlarged perforated portions or knobs, and with plain rounds or strips passing transversely through the perforated rounds, both the perforated and plain rounds being secured 50 at their ends to the outer frame, substantially as set forth.

In testimony that I claim the foregoing as my invention I have signed my name, in presence of two witnesses, this 10th day of February, 1880.

MARTIN MERKLEN.
